UNITED STATES PATENT OFFICE.

OLIVER E. BARTHEL, OF DETROIT, MICHIGAN.

PISTON.

1,139,396.

Specification of Letters Patent. Patented May 11, 1915.

Application filed May 25, 1914. Serial No. 840,681.

To all whom it may concern:

Be it known that I, OLIVER E. BARTHEL, a citizen of the United States of America, residing at Detroit, in the county of Wayne and State of Michigan, have invented certain new and useful Improvements in Pistons, of which the following is a specification, reference being had therein to the accompanying drawings.

This invention relates to pistons, and the primary object of my invention is the provision of simple and effective means, in a manner as hereinafter set forth, for dissipating the heat, of a piston to preclude excessive expansion and distortion, carburization on the piston, and undue wear upon the piston due to inequalities between the piston rod and piston head.

Another object of this invention is to provide a piston with a cross head or skirt arranged to receive the side thrusts of a piston rod, relieve the piston of excessive stresses and strains, and allow the piston to move in a uniform manner in a cylinder.

Another object of my invention is to provide a combined piston and cross head that can be advantageously used in connection with internal combustion engines, air compressors, pumps, and the cylinders of various structures, the combination tending to increase the general efficiency of an engine.

With the above and other objects in view, the invention resides in the novel construction, combination and arrangement of parts to be hereinafter specifically described and then claimed.

Reference will now be had to the drawing, wherein—

Figure 1 is a longitudinal sectional view of a piston in connection with a water-jacketed cylinder; Fig. 2 is a longitudinal sectional view of a piston especially designed for air compressors; Fig. 3 is a similar view of a piston designed for internal combustion engines; Fig. 4 is a similar view of a modified form of piston; Fig. 5 is a longitudinal sectional view of another modified form of piston, and Fig. 6 is a plan of the same.

In describing my invention by aid of the views above referred to, I desire to point out that I intend the same as merely illustrative of an example whereby my invention may be applied in practice, and I do not care to limit my invention to the precise arrangement and construction of parts

shown. The following description is therefore to be broadly construed as including substitute arrangements and construction of parts which are the obvious equivalent of those shown.

Reference will first be had to Fig. 1, wherein the reference numeral 1 denotes a portion of a cylinder having a water jacket 2 and slidably in said cylinder is a piston body 3. The outer end of the piston body 3 has side walls 4 relatively thicker than the side walls 5 of the inner end of the piston body and at the junction or meeting portions of said walls are diametrically opposed bearings or bosses 6 for the piston pin 7 of a connecting rod or pitman 8. The bearings or bosses 6 have the bores or sockets thereof open at the periphery of the piston, as indicated at 9, to permit of the piston pin 7 being placed in position to connect the piston body 3 to the rod 8, also, to allow a certain amount of heat from the walls of the cylinder to escape into the hollow piston.

The thick walls 4 of the piston body 3 are provided with annular grooves or pockets 10, said grooves or pockets being directed inwardly at a tangent to the periphery of the piston or at an angle to the longitudinal axis thereof, thereby providing each groove or pocket with an outer wall that tapers and approximates a feather or knife edge, as indicated at 11, said feather edge wall being susceptible to expansion and thereby maintaining a non-leakable sliding connection between the piston and the walls of the cylinder. Packing is eliminated and whatever wear there is upon the piston tends to maintain the feather edge of the outer walls of the grooves or pockets, consequently there is a constant and ever-ready packing after the piston has been turned up.

The advantages of the piston are more apparent in connection with special designs, one of which has been illustrated in Fig. 2, wherein 12 denotes the piston body and 13 a cross head or skirt portion thereof. The piston body has an annular recess or pocket that provides the piston with an annular wall 14, said wall tapering to a feather or knife edge that is susceptible to the action of heat fluid pressure, or compressed air and therefore is adapted to maintain a positive and non-leakable sliding joint with a cylinder wall. The piston body has diametrically opposed apertured arms 15 extending be-

tween bearings or bosses 16 forming part of the cross head or skirt 13, said arms and said bearings accommodating a piston pin 17 that permits of a connecting rod being connected to the piston, also self adjustment of the piston relative to the cross head or skirt portion thereof. This last named adjustment is an important feature and factor of my invention, as the piston is relieved 10 from any side thrust from a connecting rod or pitman and can readily accommodate itself to the walls of a cylinder. The air gap between the piston and the cross head portion thereof is also essential, as heat from 15 the piston head can pass into the cross head to be transferred to and absorbed by the cooling agent of a cylinder. This type of piston, however, can be advantageously used in connection with an air compressor, so, 20 also that type shown in Figs. 5 and 6, wherein the cross head or skirt portion of the piston has side walls thereof cut away, as at 18, thus providing a greater air gap and reducing the weight of the cross head or skirt portion. 25

In Figs. 3 and 4, there are illustrated types of pistons that can be used in connection with various grades of engines, for instance, that shown in Fig. 3 being especially 30 designed for a high grade internal combustion engine. The piston body comprises two clamping members 19 and 20, the former having apertured arms 21 loosely connected to a cross head or skirt portion 22 by a piston pin 23. The clamping member 19 has a concentric rib 24 coöperating with the peripheral edges of said member in providing an annular seat 25 for superposed or parallel packing rings 26. These rings are held 35 in proper relation by an annular flange or collar 27 of the clamping member 20, said flange or collar being set in from the edges of the member 20 to provide a seat and backing for the piston ring. To retain the piston 40 rings in position and also to connect the clamping member 20 to the clamping member 19, the member 20 has a central tongue 28 provided with an opening 29 alining with openings 30 in the arms 21. A tapering 45 pin or web shaped key 31 is driven in the openings 30 and 29 to draw the members 19 and 20 toward each other and thereby clamp the piston rings 26 in position. A cotter pin 32 or other fastening means can be employed 50 for preventing accidental displacement of the pin or key 31.

The piston rings 26 are substantially U-shaped in cross section, said rings having the outer walls 33 thereof of less height than 55 the inner walls and tapering to provide feather or knife edges, said outer walls serving functionally the same purpose as the walls 11 and 14 previously mentioned. The piston rings 26 provide grooves or pockets 60 of greater area than the grooves or pockets

10 and the manner in which said rings are assembled permit of renewal and proper adjustment of the rings.

The modification shown in Fig. 4 combines a piston similar to the outer end of the 70 piston 3 with a cross head or skirt portion. The piston proper is designated 34 and this piston can be made of steel or a more indurate material than the cross head or skirt portion 35, which can be made of cast iron. 75

Reference will again be had to Figs. 5 and 6 showing a piston body 36 as having a feather edge peripheral wall 37 extending above and below the piston body, the upper part of the wall serving the same purpose as 80 the wall 14 and the lower part as a scraper that prevents matter from adhering to the wall of a cylinder.

From the foregoing it will be observed that my invention possesses the following 85 characteristics and advantages:—First, that of having packing rings susceptible to the action of fluid pressure and air or gas pressure or air under compression in a cylinder to insure a non-leakable sliding fit. Second, 90 a cross head having a floating piston that is relieved of side stresses and strain by a connecting rod or pitman. Third, a floating piston that has novel packing rings providing 95 grooves or pockets adapted to dissipate the heat of a piston head. Fourth, a piston body having an annular tapering wall directed toward the compression end of said piston body. Fifth, a two-part piston body that has novel packing rings clamped between the parts of the body and the connecting means between the parts of the body 100 inclosed by a skirt. Sixth, a three part piston comprising a piston proper, a skirt or follower and a connection between the two 105 that also serves as a connection for a connecting rod and allows the skirt to receive side thrusts of the connecting rod.

What I claim is:

1. A piston comprising a body having an 110 annular wall formed to a feather edge, and a skirt movable relative to the wall of said piston body, whereby said piston body can adjust itself independent of said skirt.
2. A piston comprising a skirt, and a self 115 adjusting piston body connected thereto.
3. A piston comprising a body having a peripheral feather edge, and a skirt movable relative to said body and providing an air gap between said body and said skirt, 120 whereby the piston body can adjust itself independent of said skirt.
4. A piston comprising a body, a tapering wall carried thereby and providing an annular pocket directed toward the longitudinal axis of said body, and a skirt movably connected to said body. 125
5. A piston comprising a body having a compressible wall, a skirt in proximity to said body, a connecting rod extending into 130

- 5 said skirt, and means connecting said rod, piston body and skirt, whereby said piston body can adjust itself independent of said skirt.
- 5 6. A piston comprising a body, packing rings carried thereby, a connecting rod, and a skirt movably supported by said connecting rod in proximity to said piston body.
7. A piston comprising a body, tapering walls forming part thereof and providing annular pockets at a tangent to the periphery of said body, and a skirt movably connected to said piston body and providing an air gap at an end thereof.
- 10 8. A piston comprising a body, a connecting rod operatively connected to said body, and a skirt surrounding the connected end of said rod, whereby said piston body can adjust itself independent of said skirt.
- 15 9. A piston comprising a body having the periphery thereof terminating in a feather edge, and a skirt movably connected to said body and having walls in a plane with the feather edge of said body.
- 20 10. A piston comprising a body, packing rings clamped thereon and providing annular pockets, a skirt in proximity to said body and providing an air gap between said body and said skirt, and a connecting rod operatively connected to said body and said skirt.
- 25 11. A piston comprising a body having the periphery thereof provided with annular pockets directed inwardly toward the longitudinal axis of the said body, a skirt, arms carried by said body and extending into said skirt, and a connection between said body and said skirt whereby said body can adjust itself independently of said skirt.
- 30 12. A piston comprising a two-part body, clamping rings between the parts of said body and providing annular pockets, means for connecting the parts of said body, and a skirt surrounding said means in proximity to an end of said body.
- 35 13. A piston comprising a body having an annular expandable wall disposed at a tangent to the periphery of said body, a connecting rod operatively connected to said piston body, and means surrounding said connecting rod adjacent said body whereby said piston body is relieved of the side thrust of said connecting rod.
- 40 14. A piston comprising a two-part body, packing rings clamped between the parts of said body and providing annular pockets having expandable walls forming part of the periphery of said body, a connecting rod connected to said body, and a skirt movable at the connected end of said connecting rod.
- 45 15. A piston comprising a body, arms carried thereby, a connecting rod extending between said arms, a skirt, and means carried by said skirt for operatively connecting said connecting rod to the arms of said piston body.
- 50 16. A piston comprising a hollow body, a skirt in proximity thereto, a connecting rod extending into said skirt and operatively connected thereto, and means for loosely holding said piston body relative to said skirt.
- 55 17. A piston comprising a two-part body, packing rings held between the parts of said body and providing feather edge expandable walls at the periphery of said body, means for connecting the parts of said body together, a skirt adjacent said body, a connecting rod extending into said skirt, and means carried by said skirt for connecting said connecting rod and piston body.

In testimony whereof I affix my signature in presence of two witnesses.
